UNITED STATES PATENT OFFICE.

CHARLES C. RUSSELL, OF CHICAGO, ILLINOIS.

SWELL FOR AUTOMATIC ORGANS.

1,400,239.

Specification of Letters Patent. Patented Dec. 13, 1921.

Application filed April 5, 1920. Serial No. 371,282.

To all whom it may concern:

Be it known that I, CHARLES C. RUSSELL, a citizen of the United States, residing in the city of Chicago, county of Cook, and 5 State of Illinois, have invented certain new and useful Improvements in Swells for Automatic Organs, of which the following is a specification, reference being had to the accompanying drawings, forming a part 10 thereof.

The purpose of this invention is to provide in an automatic organ or like instrument which is operated automatically for musical sound production, improved means for 15 modulating or modifying the intensity or volume of musical sound delivered by the instrument. It consists in the elements and features of construction shown and described as indicated in the claims.

20 In the drawings:

Figure 1 is a diagrammatic view of a structure embodying this invention presenting parts of two opposite walls,—as front and rear,—of the casing as if folded out into 25 the plane of the intermediate wall, which is the plane of the view, showing in interior elevation the sound-emergence shutters which characterize this invention with their operating means and control-connections with 30 the tracker board; and the pneumatically operated playing devices.

Fig. 2 is a detail section at the line, 2—2, on Fig. 1.

Fig. 3 is a detail section at the line, 3—3, 35 on Fig. 1.

Fig. 4 is a diagrammatic view of a modification of the means for controlling the sound exit apertures.

Fig. 5 is a section at the line, 5—5, on 40 Fig. 1.

In the structure shown in the drawings 1 is a wall of casing inclosing the various parts of an automatic reed organ, said parts being shown diagrammatically or conventionally without attempt to indicate their 45 structure in detail, that detail structure being no part of the present invention. As thus shown in general or conventional manner, 2 is the organ reed chamber whose 50 valves are automatically controlled by motor pneumatics, 3, of a pneumatic action of which the primary pneumatic action or exhaust air chamber is seen at 4. 5 is the main air receiver or exhaust air chamber with a

tension-retaining bellows, 6, from which the 55 air is exhausted by a pumper, 7, operated by a motor, 8. Exhaust air trunks, 9, lead from the exhaust air chamber or receiver, 5, to the pneumatic action chambers, 4. An air trunk, 10, leads to the organ reed chamber, 2. 11 is the tracker board over which a perforated note sheet, 12, travels for controlling the pneumatic devices which operate the reed valves for selecting the notes to be sounded. The entire mechanism above described being inclosed within a casing, of which one walls is indicated at 1, the cavity of said casing, or the portion thereof in which the organ reed chamber and controlling valves thereof are situated becomes a 70 sound chamber,—that is, the chamber in which the sound produced by the air passing through the reeds is originated or first becomes audible. The degree to which this sound is audible outside of the casing is to 75 a large extent dependent upon the opportunity afforded for emergence of the sound waves; and such emergence is provided for in removable panels, 15 and 16, respectively at the front and rear of the casing in each 80 of which there are a multiplicity of sound apertures, 15^a, 16^a, which are controlled by shutter devices, 17, 18, mounted upon the panels, 15 and 16, at the inner side thereof and adapted to be moved transversely of the 85 apertures for closing them and opening them. Each of the shutters is provided with a retracting spring, 20, operating for holding the shutters normally at open position to permit the maximum emergence of 90 the sound waves from the sound chamber. From each shutter an operating stud or finger, 21, projects inward in position to be encountered by a finger, 22, projecting rigidly from the moving wall, 23, of a motor pneumatic, 24, said motor pneumatics, 24, 24, being controlled in a well understood manner by primary pneumatics, not shown but contained in the vacuum chambers 4^b of the pneumatic units, 4^a, which comprise the motor pneumatics, 24, 24, respectively, said primary pneumatics being connected respectively, by air ducts, 27, 27, with tracker ducts, 28 and 29, in the tracker board, 11, and controlled by perforations in the note sheet, 12, passing over the mouth of said ducts for venting them in a manner and with effect well understood, for causing the 95 100 105

motor pneumatics, 24, 24, respectively, to be collapsed whenever an aperture in the note sheet passes over and thereby uncovers the mouth of the tracker duct corresponding to the respective motor pneumatic. The collapse of the motor pneumatic which results from its being put into communication with the exhaust air chamber by the action of the primary pneumatic controlled by the note sheet and tracker duct as stated, causes its finger, 22, to encounter the projecting stud, 21, of the shutter with which it coöperates and moves the shutter in direction for closing the latter, and thereby restricting the emergence of sound through the sound exits, 15^a or 16^a.

It will be seen that at normal position,—that is, in the absence of any actuation of the motor pneumatics, 24, the maximum emergence of sound will occur, that is, the instrument will be heard to play with maximum loudness; and that upon registration of a note sheet aperture with one of the tracker ducts, 28 or 29, for controlling one of the motor pneumatics, one of the shutters being closed, the sound emergence will be diminished; and that upon the registration of apertures of the note sheet simultaneously with both the corresponding ducts, 28 and 29, of the tracker, controlling the two motor pneumatics 24, 24, both said pneumatics being operated and both the shutters moved to closed position, the emergence of sound will be reduced to the limit of control which can be effected by the shutters,—that is, the playing will be heard in the softest tone. Preferably one set of apertures,—that is, those in either the front or the rear panel, it is immaterial which,—are in the aggregate greater than those in the other panel, so that the closing of one of the shutters will diminish the sound more than the closing of the other shutter. By this means four degrees of sound volume may be produced by the instrument,—first, the maximum which will be heard when both shutters are open; second, the volume which will result from the closing of the shutter controlling the lesser or smaller number of apertures; third, a volume which will result from closing the shutter controlling the larger or larger number of apertures, and fourth, the minimum sound which will result from closing both shutters.

In Fig. 4 are shown means for producing a greater number of degrees of modification of the tone volume than can be produced by the two shutters controlling different areas of exit apertures as above described. In this modified construction a single set of sound apertures, 15^x, may be controlled by a single shutter, 31, which is operated by motor pneumatic devices adapted to give it a step-by-step movement for closing it more or less, and requiring any desired number

of steps to completely close it. This step-by-step operating mechanism may be of itself of familiar form, such as is employed for a variety of step-by-step adjustments in automatic musical instruments.

As illustrated, this step-by-step mechanism consists of two motor pneumatics, 30, 30, connected respectively for control by two tracker ducts, in turn controlled by note sheet perforations, each of said pneumatics being connected for operating a feed pawl, one of said feed pawls, 32, engaging a rack bar, 33, for feeding the shutter in one direction while the other feed pawl, 34, engages a rack bar, 35, for feeding the shutter in the opposite direction, each collapse and inflation of the motor pneumatic giving one step-feed movement to the rack bar and thereby to the shutter. The note sheets for controlling this feed device will have in the line controlling the respective tracker ducts as many apertures, in quick succession as the number of steps of closing or opening movement to be given to the shutter, the shutter in this form of device being without any controlling spring and being adapted to hold the position to which it is moved by each step movement. The pawls, 32 and 34, are retracted as shown, over a pin 38, which withdraws them from engagement with the rack bar at the limit of the retracting stroke so that the pawl thus retracted is not in a position to prevent the actuation of the rack bar in opposite direction by the other pneumatic. A friction spring, 37, operating upon the shutter prevents it from moving accidentally or by jarring of the casing from the position to which it is moved by either of the feed pawls.

It will be observed (see Fig. 5) that in both of the constructions shown the panel or panels having the sound exit apertures and carrying the shutters are removable by outward movement, which withdraws the part on the shutter which is engaged or encountered for operation by the coöperating actuating part of the motor pneumatic, and that the said coöperating parts are placed in coöperative relation by merely replacing the panel.

I claim:—

1. In an automatic organ in combination with an outer casing, tone-producing devices inclosed within the casing; pneumatically-operated playing devices within the casing for operating said tone-producing means; a note sheet for selectively controlling the playing devices; the casing having a plurality of sound exits and separate shutter means for variably closing said exits respectively; motor pneumatics in the casing and connections therefrom respectively for operating said separate shutters, and separate note-sheet-controlled ducts in the tracker for controlling said motor pneumatics re-

spectively; whereby the sound emergence to the lesser or to the greater or to sum of may be varied by being limited to either or both of said exits.

2. In the structure defined in claim 1, set my hand at Chicago, Illinois, this first 5 foregoing, said separate sound exits being of different areas, whereby the sound emergence may be varied by being limited either

In testimony whereof, I have hereunto 10 set my hand at Chicago, Illinois, this first day of April, 1920.

CHAS. C. RUSSELL.
